(57) **CLAIM**

The ornamental design for a dual-band antenna, as shown and described.

DESCRIPTION

FIG. 1 is a front elevation view of a “dual-band antenna” showing our new design;

FIG. 2 is a side plan view thereof;

FIG. 3 is a rear elevation view thereof;

FIG. 4 is a front perspective view thereof;

FIG. 5 is a front elevation view thereof, with unclaimed environment not shown; and,

FIG. 6 is a rear elevation view thereof, with unclaimed environment not shown.

The broken line in the figure drawings represents unclaimed environment only and forms no part of the claimed design.
